UNITED STATES PATENT OFFICE.

WILLIAM J. MOLLOY, OF CHICAGO, ILLINOIS.

GUN-LOCK.

No. 868,681.

Specification of Letters Patent.

Patented Oct. 22, 1907.

Application filed June 7, 1907. Serial No. 377,811.

To all whom it may concern:

Be it known that I, WILLIAM J. MOLLOY, a citizen of the United States, residing at Chicago, in the county of Cook and State of Illinois, have invented certain new and useful Improvements in Gun-Locks, of which the following is a specification.

This invention relates to gun locks for double-barrel guns, and has for its object to provide a lock which can be changed from one barrel to the other, to fire either.

10 A further object is to provide an improved form of lock, with respect to the hammer operating devices.

The invention is illustrated in the accompanying drawings, in which

Figure 1 is a vertical section of the lock. Fig. 2 is a 15 side elevation. Fig. 3 is a plan view of the lock, the stock being broken away to show the same.

Referring specifically to the drawings, 1 indicates the base or frame of the lock, and it is arranged to swing laterally upon the bottom 2 of the recess formed in the 20 stock to receive it. The frame is pivoted at the rear end, at the middle line of the stock, by a screw 9, and the front wall of the recess is made in the form of an arc of a circle to allow the lateral swing. Normally, the lock stands in position to fire the left barrel, being so 25 held by a spring 25 connected between the frame of the lock and the face plate at the side of the recess, and also held by a latch 15, with a spring thereunder, which is set in the floor of the recess and which engages in a notch in the under side of the lock frame 1. The head 30 of the latch is rounded so that it will yield when special effort is applied to the lock. The lock may be swung to the right barrel by means of a push pin 24 which is exposed through the side plate and may be pressed by the thumb to force the lock over to the right side while 35 that barrel is being fired, after which the spring 25 will swing the same back to the left barrel. The lock itself is of the kind in which the hammer is not exposed, and is self-cocking.

The hammer is indicated at 3, pivoted at 4, and it carries a stirrup 5 pivoted at 6 and connected to the main 40 spring 7 which is fastened to the rear block of the case 1 by means of the screw 8. The trigger 11 is fulcrumed at 23, and carries a thrust bar or lifter 10 which engages a toe 3^a at the base of the hammer.

45 The lifter spring is shown at 12, secured to the under side of the lifter and bearing upon an inclined tension plate 13 which is pivoted at its rear end in the lock frame and at its front end is adjustable by means of a pointed screw 14 which can be advanced or retracted 50 to vary the inclination of the plate 13 and consequently to vary the tension upon the spring 12 and the lifter in the act of firing.

The trigger spring is indicated at 27, set in the lock frame behind the plunger 26 which bears against the heel of the trigger, and returns the same to normal position after each operation.

55 17 is a back stop or idler behind the head of the trigger.

Each barrel has a firing pin 18, in proper position to be struck by the hammer, and the pins are retracted 60 by their springs 19.

20 is a safety plunger set in front of the hammer, in the front end of the lock frame, with the spring 21 behind the same. This safety plunger serves to prevent accidental drop or contact of the hammer against the 65 firing pin, which might result in an accident.

In the operation of the lock, pull on the trigger advances the lifter and cocks the hammer, and continued movement causes the lower extremity or extension of the stirrup 5 to bear down on the lifter and disengage 70 same from the toe 3^a, allowing the main spring to act to throw the hammer against the firing pin.

The manner in which the lock may be swung from one barrel to the other has been explained above. The arrangement or invention saves the cost of one lock, by 75 enabling the single lock to be used on each barrel.

Various modifications or different arrangements may be made without departing from the idea or scope of the invention as indicated in the following claims.

I claim:

1. The combination with a gun having several barrels, of a lock movable from one barrel to the other.

2. The combination with a double-barreled gun, of a lock pivoted at its rear end, behind the barrels, and means to swing the same from one barrel to the other.

3. The combination with a double-barreled gun, and a firing pin for each barrel, of a lock movable behind the barrels, from one to the other, to register its hammer with either firing pin.

4. The combination with a double-barreled gun, of a 90 lock movable from one to the other, a spring for moving the lock to one barrel, and a push button for moving the same to the other.

5. In a gun lock, the combination of a hammer having a toe, a stirrup pivoted thereto and connected to the main 95 spring and having an extension projecting downward behind the toe, and a spring-supported lifter connected to the trigger and projecting under said extension and against the toe and arranged to be pressed down by said extension and disengaged from the toe when the trigger is 100 pulled.

In testimony whereof I affix my signature, in presence of two witnesses.

WILLIAM J. MOLLOY.
